FIG. 1.

FIG. 3.

FIG. 2.

FIG. 4.

Inventor:
Walter F. Davey,
by Franklin E. Low, Atty.

UNITED STATES PATENT OFFICE

2,045,840

SHADE

Walter F. Davey, Somerville, Mass.

Application October 29, 1935, Serial No. 47,257

9 Claims. (Cl. 135—7.1)

This invention relates to a shade and particularly to a type of shade commonly known as a beach or lawn shade.

The primary object of the invention is to provide a practical and effective portable or temporary shade which may be set up easily and quickly out of doors in exposed places, as, for example, upon lawns or at the seashore and utilized as a shelter and protection against sun, 10 wind and rain.

Another object of the invention is to provide a device which, when open and in use, may be tipped into numerous positions as may be necessary to provide the protection desired, there being 15 a single swivel bracket provided at each side of the shade upon which all of the members of the shade at each side thereof are adjustably mounted.

Another object of the invention is to provide 20 a simple and effective means for holding the flexible covering of the shade tightly stretched and fastened in its open position.

Still another object of the invention is to provide a structure which may be folded or rolled 25 to occupy a minimum amount of space when it is collapsed and not in use.

Referring to the drawing:—

Fig. 1 represents a perspective view of a shade embodying my invention, said shade being illustrated in an open, tipped position.

Fig. 2 is an enlarged detail front elevation of a pivoted bracket, together with the adjacent portions of the frame members of the shade that are held in assembled relation by said bracket.

Fig. 3 is a side elevation of the portions of the structure disclosed in Fig. 2.

Fig. 4 is an enlarged front elevation of the adjacent end portions of the stretching bars for the flexible covering, and including the means for fastening and holding said bars in their extended position.

Like numerals refer to like parts throughout the several views of the drawing.

In the drawing, the numerals 5 represent upright standards preferably adapted to be inserted firmly in the ground although it is evident that they may be secured in suitable stable base members, if it is so desired. The standards 5 are slotted at their upper ends at 6 to receive cooperating clamping members 7 and 8 each preferably constructed of sheet metal and so positioned relatively to each other that a side bar 55 9 for a covering 10 of canvas or other suit-

able material may be securely clamped therebetween.

The clamping members 7 are formed with an 91 arcuate intermediate portion 11 of approximately 270°, curved to fit the periphery of the bars 9, and said members terminate in radially disposed wings 12 which extend approximately perpendicular to each other. The clamping members 8 are formed with an arcuate intermediate portion 13 of approximately 90°, also curved to fit the periphery of the bars 9, and said members terminate in radially disposed wings 14 extending approximately perpendicular to each other. The clamping members 7 and 8 are pivotally secured within the slots 6 of the standards 5 by means of bolts 15 which extend through said standards and through the depending wing portions 12 and 14 respectively of said clamping members, and said bolts 15 may be utilized as a means for varying the pressure of the clamping 20 members 7 and 8 upon the bars 9.

The side bars 9 are secured to the opposite end portions of the covering 10 within hems 16 provided at said ends, and said bars hold the end portions of the covering extended laterally.

The covering 10 is held stretched lengthwise by means of stretching bars 17 which are pivotally secured at one end thereof to wings 12 and 14 of the clamping members 7 and 8 respectively by bolts 18, said wings being positioned within 30 slots 19 provided at the ends of the stretching bars. The bolts 18 extend through the stretching bars 17 and through the wings 12 and 14 and these bolts may also be utilized as a means for varying the pressure of the clamping members 7 and 8 upon the bars 9.

Adjacent overlapping end portions of the stretching bars 17 are provided with a plurality of holes 20 and are secured together in a manner to hold the covering 10 taut by means of a 40 pin 21 or other suitable fastening member which is inserted through aligning holes 20 of said bars. The stretching of the covering 10 is accomplished before the standards 5 are inserted in the ground, and in performing this operation the stretching 45 bars 17 are first positioned crosswise to each other approximately as illustrated in dotted lines in Fig. 4 and the pin 21 is inserted through properly aligned holes 20, after which said bars are straightened relatively to each other into the 50 position illustrated in Fig. 1 and in full lines in Fig. 4.

A ring 22 which is mounted loosely upon one of the bars 17 is then moved into a position where it will encircle both of the bars 17 as illustrated 55

in Fig. 1 whereupon the bars 17 will be securely held in aligned position and the covering 10 will be stretched taut and prevented from collapsing. The shade is then ready to be mounted by inserting the standards 5 in the ground as illustrated in Fig. 1, or in a suitable base member provided therefor.

When the shade of this invention is mounted ready for use the side bars 9 and the covering 10 mounted thereon may be tipped to any angle desired at either side of the standards 5, or said covering may be located in a horizontal position if desired. In tipping the side bars 9 and covering 10 the clamping members 7 and 8 will rock in unison upon the pivotal bolts 15 and sufficient friction is provided between the contacting surfaces of the depending wings 12 and 14 and the surfaces of the slots 6 of the standards 5 to maintain said side bars and covering at any angle at which they may be tipped.

In collapsing the shade the ring 22 is first moved toward the right in Fig. 1 to permit the overlapping end portions of the stretching bars 17 to be separated. Preferably the pin 21 is a drive fit in a hole 20 of one of said bars so that it will not become accidentally disengaged from the bar and lost, and said pin 21 furthermore is of sufficient length so that the ring 22 mounted upon the same stretching bar 17 in which the pin 21 is a tight fit cannot slide off said bar and also become lost.

After the adjacent end portions of the stretching bars 17 have been separated the stretching bars and standards 5 are swung upon their respective pivotal bolts until they assume a position parallel to the side bars 9, thereupon the covering 10 may be folded between the bars and standards and the entire collapsed structure will occupy a minimum amount of space and may be easily handled and moved from place to place.

I claim:—

1. A shade of the character described comprising a pair of standards, a flexible covering pivotally mounted upon said standards, and means to stretch said covering between the standards.

2. A shade of the character described comprising a pair of standards, bars pivotally mounted upon said standards, mean to stretch said covering lengthwise between the standards, and means to fasten the stretching means in an extended position.

3. A shade of the character described comprising a pair of standards, bars pivotally mounted upon said standards, a flexible covering attached at its opposite ends to said bars, and means to stretch said covering lengthwise thereof between the bars.

4. A shade of the character described comprising a pair of standards, clamps pivotally mounted

upon said standards, side bars mounted upon said clamps, a flexible covering attached at its opposite ends to said bars and held extended therebetween, and other bars pivotally attached to said clamps to stretch said covering between the side bars.

5. A shade of the character described comprising a pair of standards, a pair of co-operating clamping members pivotally mounted to rock in unison at the top of each standard, side bars 10 mounted between said clamping members, a flexible covering attached at its opposite ends to said bars, and other bars pivotally attached to said clamping members to stretch said covering lengthwise thereof between the side bars. 15

6. A shade of the character described comprising a pair of standards, a pair of co-operating clamping members at the top of each standard, a bolt pivotally securing said clamping members to each of said standards, side bars mounted 20 between each pair of clamping members and clamped thereto by said bolt, a flexible covering attached at its opposite ends to said side bars, and other bars pivotally attached to said clamping members and to each other and adapted to 25 stretch said covering between the side bars.

7. A shade of the character described comprising a pair of standards each provided with a slot at its upper end, a pair of co-operating clamping members mounted in the slot of each standard, 30 a bolt pivotally securing said clamping members to said standards in said slots, a side bar mounted between each pair of clamping members and clamped thereto by said bolt, a flexible covering attached at its opposite ends to said side bars, 35 and other bars pivotally attached to said clamping members and to each other and adapted to stretch said covering between the side bars.

8. A shade of the character described comprising a pair of standards each provided with a slot 40 at the upper end, a pair of co-operating clamping members mounted in the slot of each standard, a bolt pivotally securing said clamping members to said standards in said slots, a side bar mounted between each pair of clamping members 45 and clamped thereto by said bolt, a flexible covering attached at its opposite ends to said side bars, other bars pivotally attached to said clamping members and to each other and adapted to stretch said covering between the side bars, means 50 to fasten the stretching bars in an extended position, and means to hold the stretching bars in alignment.

9. A shade of the character described comprising a pair of standards, a flexible covering attached at its opposite ends to said standards, and means to force said standards apart and thereby stretch said covering therebetween. 55
